[57] CLAIM

The ornamental design for a steam iron, as shown and described.

DESCRIPTION

FIG. 1 is a front perspective view of the steam iron of the present invention;

FIG. 2 is a rear perspective view of the steam iron of FIG. 1;

FIG. 3 is a front elevational view of the steam iron of FIG. 1;

FIG. 4 is a rear elevational view of the steam iron of FIG. 1;

FIG. 5 is a right side view in elevation of FIG. 3;

FIG. 6 is a left side view in elevation of FIG. 3;

FIG. 7 is a top plan view of FIG. 5; and,

FIG. 8 is a bottom view of FIG. 5.

No claim is made to surface indicia on the steam iron, which surface indicia does not form part of the claimed design.
